UNITED STATES PATENT OFFICE.

JESSE C. OSBORN, OF CHICAGO, ILLINOIS, ASSIGNOR TO GRIGSBY-GRUNOW-HINDS CO., OF CHICAGO, ILLINOIS, A CORPORATION OF ILLINOIS.

CONNECTION FOR TIMING DEVICES FOR AUTOMOBILES.

Application filed January 31, 1922. Serial No. 532,941.

This invention relates to timer connections for automobiles and has for its object to provide a new and improved device of this description.

5 The invention has among other objects to provide a connecting device for the wires of the timer, which will protect them from dust and grease and chafing and short circuiting, and which can be easily and quickly applied without special knowledge, and which is particularly adapted for Ford automobiles, and which provides for an overhead wire assembly. The invention is illustrated in the accompanying drawings, 10 15 wherein.

Fig. 1 is a view showing the coil end of the cable with the conductors which lead to the timer;

Fig. 2 is a view of the timer end of the 20 cable with the conductors sheathed when ready to be attached to the timer;

Fig. 3 is a view of the cover for the connecting ends of the wire after being folded and cut ready to be sewed;

25 Fig. 4 shows the general shape of this cover before being folded;

Fig. 5 is a side view showing the conductors connected with the timer;

Fig. 6 is an end view of the construction 30 shown in Fig. 5;

Fig. 7 is a sectional view taken on line 7-7 of Fig. 3;

Fig. 8 is a sectional view taken on line 8-8 of Fig. 3.

35 Like numerals refer to like parts throughout the several figures.

In carrying out the invention I provide a flexible cover which may be made of canvas or any other suitable material. This canvas is preferably treated to make it water-

40 proof, as by treating it with asphaltum. I have shown in Fig. 4 a piece 1, cut so as to show one way of making the cover. This piece is then folded as shown in Fig. 3, and 45 is sewed or otherwise fastened at 3 and 4, as illustrated. The inclined seam or fastening device 4 is shown in Fig. 3. This inclined portion is provided by cutting the material to form the inclined edges 4^a and 4^b, as

50 illustrated in Fig. 4, and when the device is completed, there is formed an inclined end 1^a, inclined with relation to the body of the piece or cover 1. Holes 6 are then made in the cover near one edge. The conductors are then pushed into the cover and

metallic eyelets 6^a are placed in the holes, and the ends of one conductor connected with each eyelet. There are four conductors, and these conductors are not arranged in a regular order, but they must be connected with the terminals of the timer always in the same way. By connecting the ends of these conductors with the eyelets, an electrical connection is made, and when it is desired to connect the conductors with the 60 timer 8, it is only necessary to put these eyelets over the terminals 9 of the timer, and then put on the nuts 10, which can be metallic nuts or non-metallic nuts, just as desired. I may also provide washers 14 over 65 the terminals 9, as shown in Fig. 6.

One end of the cover is closed by sewing, and the other end is left open so that the wires can be inserted therein. The portion of the cover at this open end is inclined 75 at an angle to the remaining portion, as clearly shown in Fig. 5, and this permits the connection to run at an angle from the timer so that there will be no interference with parts of the timer or associated parts. It will thus be seen that the portions of the conductors wrapped about the timer are in a different plane from the remaining portion of the conductors, and this is due to the inclined end of the cover. 80

When this is done the connection will be made, and it will always be made right, and this permits the cable 12 to be run up overhead, and keeps it out of the dust and dirt and grease, and keeps it from being worn 90 because as the timer rocks back and forth the conductors move longitudinally instead of bending, and thus the tendency of the conductors to break due to bending, is entirely obviated. 95

I have described in detail a particular construction embodying the invention, but it is of course evident that the parts may be varied in many particulars without departing from the spirit of the invention as embodied 100 in the claims hereto attached, and I therefore do not limit myself to the particular construction shown.

I claim:

1. A timer connection for automobiles 105 comprising a flexible water-proofed ribbon-like casing constructed to be wrapped around the timer, and in which the conductors to be connected with the timer are encased, said casing being made up of a suit- 110

able fabric to encase the conductors and having a series of metal fasteners secured to and supported directly by the material of the casing, each fastener being connected with one of said conductors and fitting over a terminal of the timer when the casing is wrapped around the timer.

2. A timer connection for automobiles comprising a flexible water-proofed ribbon-like casing constructed to be wrapped around the timer and in which the conductors to be connected with the timer are encased, said casing being made up of a suitable fabric to encase the conductors and having a series of metal fasteners secured to and supported directly by the material of the casing, each fastener being connected with one of said conductors and fitting over a terminal of the timer when the casing is wrapped around the timer, a yielding protective tube inserted in one end of said casing and through which said conductors extend, and suitable connectors at the ends of the conductors beyond the tube.

3. A connector comprising a group of flexible wires, a flexible sheath of flat ribbon-like form from end to end in which said wires are enclosed, said wires being provided with terminals exposed externally adjacent one end of said sheath and spaced apart longitudinally thereof, said end of said sheath being bendable circumferentially in an open loop about a timer so that the terminals align themselves with radially disposed contacts on said timer.

4. A connector comprising a group of flexible wires, a flexible sheath of flat ribbon-like form from end to end in which said wires are enclosed, metallic eyelets secured to said wires passing through apertures in said sheath near one end thereof and longitudinally spaced apart, said eyelets being clinched upon the edges of said apertures thereby anchoring said wires in said sheath and constituting electrical terminals exteriorly thereof, said end of said sheath being bendable circumferentially in an open loop

about a timer so that the eyelets align themselves with radially disposed contacts on said timer.

5. A connector comprising a group of flexible wires arranged substantially parallel, and a flat flexible sheath in which said wires are enclosed, said wires terminating at different distances from the end of said sheath, a terminal for each of said wires exposed externally of said sheath and anchoring the wire to said sheath, said sheath being of diminishing cross section proportionate to the number of wires cut by cross sections through said terminals, said sheath being bendable circumferentially about a timer so that said terminals will align themselves with radially disposed contacts on said timer.

6. A connector comprising a group of flexible wires, a flexible sheath of flat ribbon-like form at one end in which sheath said wires are enclosed, said wires being provided with terminals exposed externally adjacent the said end of said sheath and spaced apart longitudinally thereof, said end of said sheath being bendable circumferentially in an open loop about a timer so that the terminals align themselves with radially disposed contacts on said timer.

7. A timer connection for automobiles comprising a flexible casing one end of said casing being ribbon-like so as to be wrapped around the timer, in which casing the conductors to be connected with the timer are encased, said casing being made up of a suitable fabric to encase the conductors and having a series of metal fasteners secured to and supported directly by the material of the casing, each fastener being connected with one of said conductors and fitting over a terminal of the timer when the casing is wrapped around the timer.

Signed at Benton Harbor, county of Berrien and State of Michigan, this 5 day of Jan. 1922.

JESSE C. OSBORN.
